WINDOW

Jack A. Wahle, San Mateo, Calif.

Application September 30, 1946, Serial No. 700,249

4 Claims. (Cl. 20—56.4)

1

This invention relates to an apparatus for holding window panes in position in a window frame.

The objects of this invention are to provide a storm-tight sash assembly in which the panes are removable and replaceable from one side of the window frame; to provide a type of spring metal latch for holding a window in position and permitting removal of the window-pane without removal of the latch; to provide a spring metal window latch which will be visually unobtrusive and of pleasing appearance; to provide a weather-tight window including a superior weather-tight gasket; and to provide a type of window especially suitable for standardized mass production for prefabricated houses and other standard size windows.

Another object of the invention is to facilitate removal of window pane either for cleaning, removal of paint or for renewal.

Other objects and advantages of this invention will appear in the course of the following description.

In the drawing:

Fig. 1 is a front elevation of a window embodying this invention;

Fig. 2 is a side elevation in section along the line 2—2 of Fig. 1;

Fig. 3 is a side elevation in section showing an alternative form of latch; and

Fig. 4 is a detail showing the cross-section of an installed gasket.

Referring to the drawings, it will be seen that the sash 10 can be made either stationary or hung vertically, horizontally, or from a hinge. It is preferable that the openings for the glass or other panels include a flat surface 11 on which the gasket 12 is secured, an edge 13 to retain the window pane within limits, and an additional indentation or recess 14.

The latch 15 consists of strip-like sheet spring metal or plastic held to the sash 10 by a screw, rivet, or nail 16. At the edge of the sash opening the latch is bent at 17 and extends toward the window pane 18. It is bent again at 20 and terminates in the short foot portion 21, which preferably should be no longer than the width of the indentation at 14. The foot portion 21 is sloped so as to apply pressure to the pane 18 to urge it into good sealing contact with the gasket 12.

Since the latch 15 is made of spring material, a window pane 18 may be installed by simply pressing it into the frame opening or by pressing the portion 19 with the thumb until the end of short portion 21 touches the edge of the inden-

2

tation at 14. The window pane 18 is then placed into the sash opening and rests on the gasket 12. When the pane 18 is in place, the latch is released, and the foot portion 21 of the latch bears against the edge of the window pane 18 holding it firmly sealed against the gasket 12.

The latch 15 which has been described above is preferably installed along the outside edge of the sash. For the portion of the window frame 10 where there are adjoining panes (as in the lower half of Fig. 2 or the center portion of the frame in Fig. 1), there could be two such latches 15, each one holding one pane. However the preferable treatment in this case, as shown in the bottom portion of Fig. 2, is to use the latch 22, in which there is a center portion held in a manner similar to the way the latch 15 was held and where there are spring arms 19 on either side. The operation of the double latch 22 is in all respects the same as that of the latch 15.

An alternative form of latch 23 is shown in Fig. 3, where instead of the sharp corner 17 shown in latches 15 and 22, there is an arcuate bend 24 raising the latch 23 away from the sash 10 in the vicinity of the sash edge. Just as latch 22 is a special form embodying the same principles as latch 15, so there can be made a latch of the type of latch 22 containing two arcuate bends 24, each similar to the one on latch 23.

In Fig. 4 is shown an enlargement of one form of gasket 12 placed in position. This gasket 12 is made of rubber or some other resilient material. Preferably it is made of one piece for the four edges of the window, as can be readily done where these gaskets and latches are mass produced for standard sized openings. However, each gasket may be made in four strips or in one continuous strip bent around at the time of installation. The gasket 12 may be held in place by gluing it or cementing it to the edge of the frame 11, or it may be held in by nails or tacks, as at 25, distributed along portions of the gasket.

The specific form of the gasket as shown in Fig. 4 is not necessary to produce a weather-tight window in this invention. However, the type presented is of special interest as representing an ideal form of such gasket. The long arm 26 is compressed by the pane against the raised portion 27 and the pressure is thus distributed on the gasket at two points: (1) where the projecting arm 26 of the gasket joins the main portion of the gasket 12; and (2) at the point where the arm 26 rests on the raised portion 27. Thus this gasket has an advantage over an ordinary flat gasket by presenting a better sealing mem-

ber and also is an improvement over a type of gasket where there would be an arm 26 but no raised portion 27 so that although there might be satisfactory sealing there would be no division of pressure, and the force on the point where the arm 26 meets the gasket 12 would tend to break off the arm 26.

It can be seen that this type of window installation can be made inconspicuous or can be made in a design which will enhance the beauty of the window frame. Although it might be installed along all four sides of the window pane, it is not necessary to do so, for installation of the latch along two sides is sufficient, since pressure on two sides will hold the window against the gasket on all four sides. As shown in the drawing in Fig. 1, the latches are preferably installed along the horizontal edges of the panes. Although this has some advantages, the latches could also be installed along the vertical edges. Similarly they may be installed on the outside of the window frame instead of on the inside if that should be desirable.

It will be apparent that there are other equivalent forms in which the latches 15, 22, and 23 could be made without departing from the spirit of this invention, and throughout the invention there may be changes, apparent to persons learned in the art, in size, material, form, and other matters which still would not depart from the spirit of this invention or from the scope of its claims.

I claim:

1. A window construction including a frame, an opening in said frame, having a flange with a sealing gasket thereon, a pane in said opening, a resilient pressure member secured to the edge of said opening, said pressure member having a foot portion applying pressure along the edge of said pane to press it against said gasket, said frame having a recess to receive said pressure member when it is depressed while inserting or removing said pane.

2. The window construction claimed in claim

1, in which the gasket comprises a forked strip having a lower heel portion which fits on said flange, said heel portion having a mound extending linearly and parallel to the fork of said strip, said forked strip also having an upper arm portion projecting from said fork further than the distance from the fork to the mound, so that said arm portion rests on said mound when pressure is exerted on it by the pane and the resilient pressure member.

3. A window construction including a frame having an opening therein and a flange with a sealing gasket thereon, a pane in said opening, a strip metal spring latch member secured to said frame along any two opposite edges of said opening, said latch member having a foot portion applying pressure along the edge of said pane to press it against said gasket, said frame having a recess to receive said latch member when it is depressed while inserting or removing said pane.

4. A window construction including in combination a frame having an opening and a moulding around said opening having two successively stepped-in flanges, a resilient gasket fastened to the flange immediately adjacent to said opening, a pane in said opening and resting on said gasket, and a resilient pressure member secured to said frame adjacent to the edge of said opening and having a foot portion applying pressure along the edge of said pane to press it against said gasket and being adapted to fit into the space above the flange farther from the opening when depressed while inserting or removing said pane.
